DEASPHALTING PROCESS

John Weikart, Westfield, N. J., assignor to Standard Oil Development Company, a corporation of Delaware

Application February 19, 1952, Serial No. 272,429

2 Claims. (Cl. 196—14.11)

1

The present invention is concerned with an improved process for the removal of asphaltic constituents from residual oils whereby increased yields of higher quality lubricating oils and fuel oils are obtained. The present invention is also concerned with an improved process for the preparation of satisfactory feed stocks for fluid cracking operations, whereby higher quality hydrocarbon products boiling in the gasoline and heating oil boiling ranges are obtained by an efficient operation. In accordance with the present invention, a residual oil is air blown under controlled critical conditions. Asphaltic constituents are then removed from the air blown residuum and the resulting high yield deasphalted product utilized as a high quality lube oil, as a high quality fuel, or utilized in a catalytic cracking operation.

It is well known in the art to treat mineral oils by various processes in order to remove undesirable high boiling and asphaltic constituents from these oils. For example, it is known to employ light hydrocarbon solvents, as for example, hydrocarbons such as propane and butane, in order to remove undesirable constituents, such as, asphaltic constituents therefrom. In these operations various temperatures and pressures are employed, as well as various solvent to oil ratios. It is also known in the art to use various other processes for the removal of carbon, and ash-forming constituents therefrom in order to prepare high quality lube and fuel oils. Other processes have also generally been directed toward the preparation of satisfactory high boiling feed stocks for a fluid catalytic cracking operation.

It has now been discovered that undesirable high boiling constituents may be efficiently removed from feed stocks boiling in the reduced crude boiling range, providing the reduced crude or residual oil is air blown under controlled conditions prior to deasphalting with a deasphalting solvent, as for example, propane. The process of the present invention, producing increased yields of deasphalted oil, may be readily understood by reference to the drawing illustrating one embodiment of the same.

Referring specifically to the drawing, a feed oil, as for example, a West Texas crude, is introduced into distillation zone 1 by means of feed line 2. Temperature and pressure conditions in zone 1 are adjusted to secure the desired fractionation of the crude oil. Low boiling hydrocarbon gases are removed overhead from zone 1 by means of line 3; a hydrocarbon fraction boiling in the light naphtha range is removed by means of line 4, a hydrocarbon fraction boiling in the heavy naphtha range is removed by means of line 5, while a gas oil fraction is removed by means of line 6. A fraction boiling in the reduced crude boiling range, as for example, in the range above about 600° to 700° F., preferably boiling in the range above 750° F., is segregated as a bottoms fraction by means of line 7. It is

2

to be understood that zone 1 may comprise any suitable number and arrangement of distillation zones or stages.

In accordance with the present invention, the high boiling reduced crude is air blown in zone 10 under controlled conditions as hereinafter described. The air blown residuum is introduced into a deasphalting zone 8 wherein it is preferably countercurrently contacted with a deasphalting solvent, as for example, propane which is introduced into deasphalting zone 8 by means of line 9. Temperature and pressure conditions in zone 8 are adjusted to secure the desired removal of asphaltic constituents from the residual oil. A residual oil-propane mixture is removed overhead from zone 8 by means of line 13 and introduced into a distillation zone 15. Temperature and pressure conditions in zone 15 are adjusted to remove overhead by means of line 56 propane which is preferably recycled to zone 8. A residual fraction is removed from the bottom of distillation zone 15 by means of line 51 and preferably combined with a portion of the gas oil stream withdrawn from zone 1 which is introduced into line 51 by means of line 52. This gas oil may be removed from the system by means of line 60. Deasphalted oil may be removed by means of line 61 and utilized as a high quality fuel or lubricating oil.

30 The asphaltic constituents are removed from zone 8 by means of line 53 and passed to a distillation zone 54, wherein a separation is made between the propane and the asphaltic constituents. The propane is removed overhead by 35 means of line 55 and preferably recycled to zone 8 while the asphaltic constituents are removed as a bottoms by means of line 56 and further refined or handled as desired. It is to be understood that zones 8, 15 and 54 may comprise any 40 suitable number and arrangement of stages.

The present invention is broadly concerned with an improved process for the removal of undesirable high boiling constituents and asphaltic constituents from residual oils. The invention 45 comprises utilizing in conjunction with conventional solvents, an air blowing operation. The resultant deasphalted product, as pointed out heretofore, is suitable for the production of high quality lube oils, high quality fuel oils, and 50 is particularly adapted as a feed stock to a fluid catalytic cracking operation.

The deasphalting solvent may comprise low boiling hydrocarbons, as for example those containing from 2 to 5 carbon atoms in the molecule, 55 or mixtures thereof. Particularly desirable solvents comprise propane and butane. The amount of solvent used per volume of oil may vary from 4 to 10, preferably in the range from 6 to 8 volumes of solvent per volume of oil. The mixture is generally heated to a temperature in the range from about 110° F. to 160° F., preferably to a temperature in the range from 110 to 140° F. The deasphalting operation may comprise a batch operation or a countercurrent treating operation

wherein the oil is introduced into the top of the tower, the propane is introduced into the bottom of the tower, and wherein deasphalted oil is removed from the top of the tower and asphaltic constituents from the bottom of the tower. In conducting an operation of this character, a temperature gradient is preferably maintained throughout the tower.

As heretofore disclosed, the deasphalted residual fraction withdrawn from zone 15, in accordance with a specific adaptation of the present invention, may be combined with a portion of the gas oil fraction segregated in zone 1 and introduced into a fluid catalytic cracking operation.

The fluid catalytic cracking operation comprises three sections: cracking, regeneration, and fractionation. The cracking reaction takes place continuously in one reactor, the spent catalyst being removed continuously for regeneration in a separate vessel, from which it is returned to the cracking vessel. Continuity of flow of catalyst as well as of oil is thus accomplished, and the characteristic features of fixed-bed designs involving the intermittent shifting of reactors through cracking, purging, and regeneration cycles are eliminated.

Regenerated catalyst is withdrawn from the regenerator and flows by gravity down a standpipe, wherein a sufficiently high pressure head is built up on the catalyst to allow its injection into the fresh liquid oil stream. The resulting mixture of oil and catalyst flows into the reaction vessel, in which gas velocity is intentionally low, so that a high concentration of catalyst will result. The cracking that takes place results in carbon deposition on the catalyst, requiring regeneration of the catalyst. The cracked product oil vapors are withdrawn from the top of the reactor after passing through cyclone separators to free them of any entrained catalyst particles, while the spent catalyst is withdrawn from the bottom of the reactor and is injected into a stream of undiluted air which carries the catalyst into the regeneration vessel. The products of combustion resulting from the regeneration of the catalyst leave the top of this vessel and pass through a series of cyclones where the bulk of the entrained catalyst is recovered. The regenerated catalyst is withdrawn from the bottom of the vessel to complete its cycle.

Again referring specifically to the drawing, in accordance with a specific preferred adaptation of the present invention, the treated oil removed by means of line 51 is introduced into a catalytic cracking zone 22.

Temperature and pressure conditions in cracking zone 22 are adjusted to secure the desired conversion of the feed oil. Cracked products are removed overhead from zone 22 by means of line 23 and passed into a fractionation zone 24. Temperature and pressure conditions in fractionation zone 24 are adjusted to remove overhead by means of line 25 hydrocarbon constituents boiling in the gasoline and lower boiling ranges. This stream is passed to a stabilizing unit where a gasoline fraction of the desired volatility is segregated. A heating oil fraction is removed by means of line 26 while a fraction boiling in the light cycle oil boiling range is removed by means of line 27. A bottoms fraction or heavy cycle oil is removed by means of line 28 and handled as desired. Spent catalyst is removed from the bottom of zone 22 by means of line 29 and passed into a regeneration zone 20 by means of line 21. Sufficient air is introduced into the system by

means of line 32. Regenerated catalyst is removed from the bottom of zone 30 by means of line 33 and passed to the reactor along with the feed by means of line 17.

The invention is broadly concerned with the removal of undesirable materials from petroleum oils, particularly from petroleum oils boiling in the reduced crude boiling range. Petroleum oils treated in accordance with the present invention are particularly adapted as feed stocks for a catalytic cracking reaction. Although the invention may be adapted for the treatment of mineral oils boiling over wide ranges as pointed out above, it is particularly adapted for the treatment of oils boiling above about 750° F., preferably boiling above about 860° F.

As discussed above, the invention is particularly concerned with an improved operation which comprises the air blowing of a reduced crude prior to deasphalting the same. It is well known in the art to produce cracked naphthas by a fluidized solids catalytic operation wherein the cracked product comprises constituents boiling in the motor fuel boiling range, as for example, below about 430° F. The cracked product also comprises normally gaseous constituents, as for example, those containing three carbon atoms and less in the molecule. The fluidized solids technique for processing feed fractions, as for example, gas oils, heavy residuums and other feed stocks for the production of hydrocarbon fractions boiling in the motor fuel boiling range is a conventional one. As pointed out heretofore, the system of a fluidized solids technique comprises a reaction zone and a regeneration zone, employed in conjunction with a fractionation zone. The reactor and the catalyst regenerator are arranged at approximately an even level. The operation of the reaction zone and the regeneration zone is conventional, which is as follows:

An overflow pan is provided in the regeneration zone at the desired catalyst level. The catalyst overflows into a withdrawal line which preferably has the form of a U-shaped seal leg connecting the regeneration zone with the reaction zone. The feed stream introduced is usually pre-heated to a temperature in the range from about 500° to 650° F. in exchangers in heat exchange with regenerator flue gases which are removed overhead from the regeneration zone, or with cracked products. The heated feed stream is withdrawn from the exchangers and introduced into the reactor. The seal leg is usually sufficiently below the point of feed oil injection to prevent oil vapors from backing into the regenerator in case of normal surges. Since there is no restriction in the overflow line from the regenerator, satisfactory catalyst flow will occur as long as the catalyst level in the reactor is slightly below the catalyst level in the regenerator when vessels are carried at about the same pressure. Spent catalyst from the reactor flows through a second U-shaped seal leg from the bottom of the reactor into the bottom of the regenerator. The rate of catalyst flow is controlled by injecting some of the air into catalyst transfer line to the regenerator.

The pressure in the regenerator may be controlled at the desired level by a throttle valve in the overhead line from the regenerator. Thus, the pressure in the regenerator may be controlled at any desired level by a throttle valve which may be operated, if desired, by a differential pressure controller. If the pressure differential between the two vessels is maintained at a mini-

mum, the seal legs will prevent gases from passing from one vessel into the other in the event that the catalyst flow in the legs should cease.

The reactor and the regenerator may be designed for high velocity operation involving linear superficial gas velocities of from about 2.5 to 4 feet per second. However, the superficial velocity of the upflowing gases may vary from about 1-5 and higher. Catalyst losses are minimized and substantially prevented in the reactor by the use of multiple stages of cyclone separators. The regeneration zone is provided with cyclone separators. These cyclone separators are usually from 2 to 3 and more stages.

Distributing grids may be employed in the reaction and regeneration zones. Operating temperatures and pressures may vary appreciably depending upon the feed stocks being processed and upon the products desired. Operating temperatures are, for example, in the range from about 800° to 1000° F., preferably about 850°-950° F., in the reaction zone. Elevated pressures may be employed, but in general pressures below 100 lbs. per sq. in. gauge are preferred. A catalyst holdup corresponding to a space velocity of 1 to 20 weights per hour of feed per weight of catalyst is utilized. A preferred ratio is 2 to 4. Catalyst to oil ratios of about 3 to 10, preferably about 6 to 8 by weight are used.

The catalytic materials used in the fluidized catalyst cracking operation, in accordance with the present invention, are conventional cracking

wherein the weight per cent of the alumina is in the range from about 5 to 20%. Another preferred catalyst comprises silica-magnesium where the weight per cent of the magnesia is about 5% to 20%. These catalysts may also contain a third constituent, as for example, ThO_2 , WO_3 , MoO_3 , BeO , Bi_2O_3 , CdO , UO_3 , B_2O_3 , SnO_2 , Fe_2O_3 , V_2O_5 , MnO , Cr_2O_3 , CaO , Ti_2O_3 , MgO and Ce_2O_3 present in the concentration from 0.05% to 0.5%. The size of the catalyst particles is usually below about 200 microns. Usually at least 50% of the catalyst has a micron size in the range from about 20-80. Under these conditions with the superficial velocities as given, a fluidized bed is maintained wherein the lower section of the reactor, a dense catalyst phase exists while in the upper area of the reactor a dispersed phase exists.

The above described operation, as pointed out, has not been entirely satisfactory for cracking 20 heavy oils such as a reduced crude due to excessive formation of carbon and ash on the catalyst. However, by air blowing the reduced crude and deasphalting the same, unexpected desirable results are secured.

25 The present invention may be more fully understood by the following example illustrating the same:

Example

30 Various residuums were air blown at 550° F. for various time periods. The results of these operations are as follows:

Oxidation Period, Hours	0	0.5	1	2	3	5	8
Inspections of Pitch:

It is to be noted that air blowing of the residuum for one hour gave excellent results in that the yield was increased from 55 vol. per cent to 65 vol. per cent. On the other hand, air blowing for five hours gave adverse results. It is to be noted that air blowing the residuum for one hour resulted in increasing the naphtha insoluble content to the level of the Conradson carbon on the original pitch. Thus, the extent of the air blowing may be somewhat determined by this criteria.

The present invention is broadly concerned with an improved deasphalting operation of heavy residua whereby the yields are materially increased. The temperatures employed in the air blowing process are in the range from about 450° F. to 700° F., preferably in the range from 500° F. to 600° F. The time of air blowing will somewhat depend upon the temperature utilized, but in general should not exceed about 3 hours and preferably should be in the range from $\frac{1}{2}$ to 2 hours.

What is claimed is:

1. Process for the production of hydrocarbon constituents boiling in the motor fuel boiling range from a feed oil boiling above about 750° F., comprising air blowing said feed oil for a time period of from about $\frac{1}{2}$ to 2 hours at a tempera-

ture in the range from 450 to 700° F., thereafter removing asphaltic constituents from the air blown oil, then contacting said oil with a suitable fluidized cracking catalyst at elevated temperatures and pressures adapted to crack the oil and produce hydrocarbons boiling in the motor fuel boiling range, passing said cracked product to a distillation zone and segregating hydrocarbon constituents boiling in the motor fuel boiling range.

2. Process as defined by claim 1 wherein the feed oil is an oil which boils above about 860° F.
